METHODS FOR PIVOTALLY ATTACHING COVER
SECURING LUGS ON A DRUM

Charles A. Uncapher, Chicago, Ill., and Harry E. Lesher, Van Wert, Ohio, assignors to Continental Can Company, Inc., New York, N.Y., a corporation of New York

Original application June 26, 1962, Ser. No. 205,448, now Patent No. 3,168,973, dated Feb. 9, 1965. Divided and this application Mar. 30, 1964, Ser. No. 355,555

6 Claims. (Cl. 29—437)

This is a division of application Serial No. 205,448, filed on June 26, 1962, now Patent No. 3,168,973.

This invention relates to fiber drums, of the type having covers or closure members, and more particularly relates to novel methods for pivotally attaching cover securing lugs on the fiber drums without causing damage thereto.

The completed drums of the present invention are particularly adapted for the storage and shipment of lard, vegetable shortening and the like. The drum bodies preferably are made from fiber tubing composed of several plies or windings of paperboard. The interior surfaces of the drum bodies are further provided with a lining or coating so as to prevent the absorption of the lard or comparable fill and this not only prevents the drums from taking on an undesirable appearance, but further tends to prevent the lard from oxidizing and becoming rancid.

The invention particularly deals with novel methods of connecting a fastening lug structure to the chime of a fiber drum such that the lug structure serves by a snap-over engagement to hold a cover or closure member in closed position over a drum end. Fiber drums are usually provided with a closure member at one end thereof which may be opened for access to the material therein, and later again closed. In holding such a closure or cover on the end of a drum of this type, it has been known to provide swingable members which are fastened to the drum side wall and which engage the closure member by snap-fit engagement, or the like, so as to retain the cover in tight relationship on the end of the drum over which the closure is applied. These fastening lugs of prior art devices have, however, been attached directly through the side wall of the drum and, therefore, have necessitated a puncturing of the body side wall. In those cases where lining is already provided on the inner surfaces of the drum body, the direct mounting thereon of a fastening lug which pierces the lining would necessitate a patching of the pierced portions. Also, in those cases where the lining or coating is applied to the inner surfaces of the drum after these lugs have been attached thereto, those areas pierced by the mounting of the fastening lugs must be covered or patched so as to present a smooth surface for either the coating or the lining.

It is an object of this invention to provide a novel method of joining a fastening lug to the metal chime of a drum, the method comprising providing the chime with outwardly projected beads presenting opposing recesses, providing the lug at one end with outwardly projecting mounting ears, and presenting the lug ears in pivotal engagement in the ear recesses.

Another object of the invention is the provision of a novel method of joining a fastening lug to the metal chime of a drum, the chime having spaced beads therein providing opposing recesses, and the lug having outwardly projecting mounting ears at one end thereof and being bent into V-shape intermediately of the ears, the method comprising placing the lug with its ears between the bead recesses and flattening the V-shaped lug portion to present the lug ears in pivotal engagement in the recesses.

2

A still further object of the invention is to provide a novel method of the character stated wherein the chime is provided with an open slot between the beads of each cooperating pair and the beads open through the back of the chime, the presentation of the lug ears in the bead recesses being by the way of insertion of a lug through a chime slot and engagement of the lug ears in the bead recesses through the open backs of the beads.

With the above and other objects in view that will hereinafter appear, the nature of the invention will be more clearly understood by reference to the following detailed description, the appended claimed subject and the several views illustrated in the accompanying drawing.

15 In the drawing:

FIGURE 1 is a fragmentary elevational view of the drum of the present invention with parts broken away for clarity and, in particular, showing one form of means for attaching the fastening lug to the metal chime of the drum.

20 FIGURE 2 is a fragmentary vertical sectional view of the embodiment shown in FIGURE 1, the section being taken on the line 2—2 of FIGURE 1.

FIGURE 3 is a view similar to FIGURE 1 with parts 25 broken away for purposes of clarity and showing another embodiment of the fastening lug of the present invention in an intermediate stage of its attachment to the metal chime of the fiber drum, the lug being shown as flattened out in dot and dash lines, with its ears in place in the bead recesses.

30 FIGURE 4 is a fragmentary vertical sectional view illustrating the embodiment shown in FIGURE 3 with the fastening lug embodiment of FIGURE 3 flattened in final secure pivoted attachment to the metal chime.

35 FIGURE 5 is a horizontal section taken on the line 5—5 of FIGURE 3.

Referring to the drawing in detail, there is illustrated therein a drum 5 having a side wall 6 made up of a tube of several plies or convolute windings of paperboard or 40 the like. The interior surfaces of the drum 5 are preferably provided with a coating or lining 7 which is impervious to the products to be carried in the drum, thus to protect the side wall 6 from product absorption in cases where the drum is to be utilized in carrying lard, vegetable shortening, or like fill. Other products may, 45 of course, be contained in the drum 5, it being obvious that petroleum jelly, flaked or powdered chemicals and many other materials may be packaged therein.

A cut end edge 8 of the side wall 6 is covered by or 50 enclosed in a metal chime 9 which is telescoped over the side wall 6, as by turning portions of the chime 9 over the edge 8 and into compression therewith as shown in FIGURE 2. The metal chime 9 extends partially downward along the side wall 6 and forms a metal band around the top of the drum 5. Further associated with the drum 5 is a cover or closure member 10 held in place by a plurality of fastening lugs 11. The cover or closure member 10 may be of conventional design normally provided with a strengthening depression or rib 12, an upwardly curved portion or channel 13 for engagement over the metal chime 9, and a downwardly extending side wall or skirt portion 14 which embraces the upper portion of the chime and terminates in an upwardly turned hem or curl 15.

60 About the periphery of the chime 9 there are provided a plurality of pairs of spaced beads 16, the beads of each pair being placed in opposition one to another. Each bead 16 is formed from an outwardly displaced or projected portion of the metal chime 9 and thus forms an interior recess 17, the recesses provided by each 65 cooperating pair of the beads 16 opening in opposition one to the other through the opposed cut edges 18 of the

beads. The beads 16 and the recesses 17 therein may be formed by a punching operation prior to the placement of the chime 9 on the side wall 6 of the drum, or such beads may be formed along the chime after it has been attached to the drum 5 by cutting spaced longitudinal lines in the chime and outwardly projecting bead forming portions of the chime as by employment of suitable tool means such as a pair of tapered pliers.

It thus becomes apparent that by equipping the fastening lug members 11 with ears 19 which project from either side at one end 20 thereof, a suitable means by which the fastening lugs 11 may be pivotally mounted on the metal drum 9 is provided. In this manner, fastening lugs may be mounted on the chime so as to be swingable from an inactive position in which they do not engage the closure member 10 of the drum 5 to an active, cover securing position such as is illustrated in FIGURES 2 and 4 of the drawing.

It should be noted that the action between the fastening lugs 11 and the closure member 10 may be that of a snap over engagement, as shown in FIGURE 2, or it may be of a mere contact fit which is then later tightened or secured by a downward deformation of the lug end 21 of FIGURE 2 or the lug end 22 of FIGURE 4, it being apparent that either design of the fastening lug end is applicable for both snap-fit and deformation secured engagement over the drum cover. A ring-like deformation or pressing member (not shown) may be utilized in deforming the ends 21 or 22 of the fastening lugs 11 downwardly into a more secure holding engagement over the closure member 10 when such an operation is to be simultaneously carried out upon the plurality of fastening lugs 10 with which a drum chime is equipped.

Referring now specifically to FIGURES 1 and 2 of the drawing, one embodiment of the present invention is disclosed therein. In this embodiment the metal chime 9 is provided with a slot 23 between each cooperating pair of beads 19 and through which a fastening lug 11 may be threaded prior to the mounting of the metal chime 9 over the end 8 of the fiber side wall 6. Each slot 23 is generally rectangular in form, as shown in FIGURE 1, and extends entirely across between the spaced beads of a cooperating pair, from one cut edge 18 to the opposing cut edge 18. In this manner, the recesses 17 which are formed in the outwardly projecting beads 16 merge with or open into the slot 23. This, in effect, forms a continuous opening (17, 23, 17) through the metal chime 9. As was above indicated, the fastening lug 11 is placed or mounted with its end 21 being initially presented through the slot 23 until the ears 19 engage in the bead recesses 17 as shown in FIGURE 1. The chime is then mounted on the side wall 6 of the drum 5. It will be apparent that in this manner the fastening lugs 11 become pivotally secured to the drum in a position along its side wall 6 whereby said lugs can be swung upwardly to engage over and secure a closure member 10 on the drum in the manner previously described. It should be noted further that each fastening lug 11 includes a curved upper portion 24 which conforms to and makes contact with the upwardly curved portion or channel 13 of the closure member 10, a generally straight upper portion 25 downwardly extending therefrom, and a lower portion 26 of generally straight configuration which is dependent from the upper portion 25 and forms an obtuse angle therewith. The lug portions 25 and 26 may, however, form a more or less smooth curve which is outwardly spaced from the side wall 6 if desired.

It should be further noted in the embodiments specifically shown in FIGURES 1 and 2 of the drawing that the ears 19 project from either side of the lower portion 20 of each fastening lug 11 and that the general configuration of the fastening lug 11 is strap-like and of equal width along its longitudinal extent except for the projection of the ears 19 as above mentioned.

Referring now to FIGURES 3 and 4 of the drawing,

there is therein shown a modified form of fastening lug 11a and in connection therewith, another procedure for attaching the fastening lug to the metal chime 9. The fastening lug 11a is constructed similarly to the previously described fastening lug 11 with the exception that its lower generally straight portion 26a which corresponds to portion 26 of fastening lug 11 is of a lesser width. The portion 26a is defined by sides which converge from the full width at section 25a downwardly toward a lower terminus from each side of which an ear 19 projects. The lower lug portion 26a is also folded or bent to a V-section about a median fold line 28 as shown in FIGURE 5 whereby the lateral spacing of the ears 19 is contracted so that the ears may be readily placed between the recesses 17 of the beads 16 as shown in FIGURES 3 and 5. Thus, when the V-bent portion 26a is flattened or restored to its initial condition as shown in FIGURE 4 of the drawing, the ears 19 will be projected laterally into the recesses 17, thus to secure the fastening lug 11a in its desired pivotal mounting on the metal chime 9. This may be accomplished by hammering the lower portion 26a of the fastening lug 11a in the vicinity of the fold line 28, flattening said lower portion and thus, in effect, driving the ears 19 laterally into the receiving recesses 17.

It will be apparent from the foregoing that there has been provided novel methods for pivotally attaching cover securing lugs on a fiber drum of the type having a metal chime on one end thereof. One method is disclosed in FIGURES 1 and 2 wherein the slot 23 is formed in the chime 9 between the pair of beads 19. The method comprises the steps of threading the strap-like portion of the lug 11 through the chime slot 23 to engage the ears 19 of the lug within the recesses formed by the beads. Another method is illustrated in FIGURES 3-5 wherein the chime 9 is cut along spaced parallel lines 18. In this form, the chime 9 is not provided with a slot, such as the slot 23 in FIGURE 1, and the fastening lug 11a is bent to a V-section along the fold line 28, as is shown in FIGURE 5, and the fastening lug 11a is positioned on the chime by hammering the lower portion 26a so as to drive the ears 19 laterally into the receiving recesses 17.

While a preferred form of container, cover and lug assembly and preferred methods of assembling the same are disclosed in detail herein, it is to be understood that variations in the disclosure of the method steps and part arrangements may be provided without departing from the spirit and scope of the invention as defined in the appended claimed subject matter.

We claim:

1. The method of joining a closure fastening lug to the chime of a drum, said lug being of generally strap-like configuration and having an ear projecting from either side at one end thereof, said one end being V-shaped in cross-section, and said chime being of a shape corresponding to the shape of the end of said drum and having a pair of outwardly extending spaced beads recessed for engagement with said ears, said method comprising aligning said ears in position between said beads and flattening said one end so as to increase the spacing of said ears and present them in the recesses formed by said beads whereby the lug is held in pivotal relationship with the chime.

2. The method of mounting a cover fastening lug and a metal chime on a drum having an open end, said lug having a generally strap-like configuration, one end of said lug having an ear projecting from each side thereof for engagement with beads formed along the surface of the metal chime, and said chime being of a shape corresponding to the shape of the end of said drum and having a pair of outwardly projected beads defining recesses for receiving said lug ears and a slot extending between said pair of spaced beads and merging at either side thereof with said recesses, said method comprising threading the strap-like portion of the lug through the chime slot to engage the ears of the lug within said recesses whereby the lug becomes pivotally attached to the chime, and se-

curing the chime over the open end of the drum thus pivotally mounting the lug on the drum adjacent the open end thereof.

3. The herein described method of pivotally attaching cover securing lugs on a drum which comprises providing a chime for attachment to an end portion of the drum, said chime being of a shape corresponding to the shape of the end portion of the drum, providing in said chime at least one pair of spaced and outwardly projecting beads presenting opposing open end portions opening laterally into receiving recesses with said recesses opening inwardly through the chime and with a slot extending through the chime between the beads and merging into the bead recesses, providing a plate-like securing lug shaped at one end for securing engagement over a cover placed over the end portion of the drum and at its other end with two oppositely and laterally directed mounting ears, placing the lug ears in pivoted engagement in said bead recesses by threading said one end of the lug through the slot to an extent for placing said ears in said recesses, and securing the chime over the open end of the drum thus pivotally mounting the lug on the drum adjacent the end portion thereof.

4. The herein described method of pivotally attaching cover securing lugs on a chime which comprises providing a chime for attachment to an end portion of a drum, said chime being of a shape corresponding to the shape of the end of said drum, providing in said chime at least one pair of spaced and outwardly projecting beads presenting opposing open end portions opening laterally into receiving recesses, providing a plate-like securing lug shaped at one end for securing engagement over a cover placed over the end portion of the drum and at its other end with two oppositely and laterally directed mounting ears, bending the end portion of the lug bearing the mounting ears into V-section along a median line to con-

tract the lugs to a spacing readily receivable between the beads, placing said last named lug end portion between the beads and flattening the V-section thereof to project and place the mounting ears in pivoted engagement in the bead recesses.

5. The herein described method of pivotally attaching cover securing lugs on a chime which comprises providing a chime for attachment to an end portion of a drum, said chime being of a shape corresponding to the shape of the end portion of the drum, providing in said chime at least one pair of spaced and outwardly projecting beads presenting opposing open end portions opening laterally into receiving recesses, providing a plate-like securing lug shaped at one end for securing engagement over a cover placed over the end portion of the drum and at its other end with two oppositely and laterally directed mounting ears, and placing the lug ears in pivoted engagement in said bead recesses, the beads being provided by parallel longitudinal slitting of the chime and outward shaping of chime portions oppositely endwise of the slitting.

6. The method defined in claim 4 wherein the beads are provided by parallel longitudinal slitting of the chime and outward shaping of chime portions oppositely endwise of the slitting.
